UNITED STATES PATENT OFFICE.

JOSEPH G. McCONAGHY, OF WASHINGTON, DISTRICT OF COLUMBIA, ASSIGNOR OF ONE-THIRD TO WINFIELD A. WILSON AND ONE-THIRD TO ANNA V. McCONAGHY, OF WASHINGTON, DISTRICT OF COLUMBIA.

TOY.

937,323.

Specification of Letters Patent. Patented Oct. 19, 1909.

Application filed April 3, 1908. Serial No. 424,952.

To all whom it may concern:

Be it known that I, JOSEPH G. McCONAGHY, a citizen of the United States, residing at Washington, in the District of Columbia, have invented new and useful Improvements in Toys, of which the following is a specification.

This invention relates to a toy designed to be used for producing a noise or report somewhat like that of a pistol or firecracker without, however, employing an explosive so that the usual dangers of firecrackers or other pyrotechnic articles are avoided.

The invention has for one of its objects to provide a toy of this character which is comparatively easy and inexpensive to manufacture, readily manipulated by a child, and affording considerable amusement and entertainment.

A further object of the invention is the provision of a toy in the nature of a hollow body having a vibrant head such as rubber, raw hide or the like on which acts a striking element whereby a loud report can be produced, the said element being a resilient member disposed across the head and adapted to be drawn outwardly or away from the latter and then released so as to strike against the head.

With these objects in view and others, as will appear as the description proceeds, the invention comprises the various novel features of construction and arrangement of parts which will be more fully described hereinafter and set forth with particularity in the claims appended hereto.

In the accompanying drawings, which illustrate certain of the embodiments of the invention, Figure 1 is a perspective view of the toy. Fig. 2 is a central vertical section thereof. Fig. 3 is a plan view of the body. Fig. 4 is a perspective view of the striking element. Fig. 5 is a fragmentary sectional view showing the striking element in raised position with respect to the head of the toy.

Similar reference characters are employed to designate corresponding parts throughout the several views.

Referring to the drawings, 1 designates a tubular body or barrel made of wood, paper, metal or other suitable material and formed at its upper end with a bead 2 and having immediately below the same an annular groove 3, the lower end of the body

being closed by a bottom piece 4 fitted thereto. Stretched over the upper open end of the body 1 is a vibrant head 5 of raw hide, rubber, metal, paper or the like, which is in the form of a disk of such diameter as to entirely cover the top of the body and enter the groove 3 thereof, there being a band 6 extending around the head to retain the marginal portion of the latter in the groove.

Extending transversely over the head 5 is the striking element 7 which may be a strip of rubber or other elastic material and arranged with its extremities inserted under the band 6 so as to securely hold the element in place. This element may be provided with a central stem or grip 8 whereby the element can be pulled outwardly away from the head and then released to permit the element to strike the latter for producing a report. The stem 8 may be made to resemble a fuse of a firecracker and the body of the toy may be made to resemble in appearance the form of an ordinary firecracker. In the present instance, the striking element 7 is so designed as to produce two rapidly succeeding reports, and for this purpose, the elastic strip is divided longitudinally by a slot 9 and the lower end of the stem is formed into bifurcations each connected with one half of the elastic strip. One bifurcation is slightly longer than the other as shown in Fig. 5, so that it will strike the head when the stem is released a short period before the other bifurcation, thus producing two reports. The stem 8, which may be of rubber, has the longer bifurcation reduced at 11 so that this bifurcation will be more readily compressed when the striking element bears on the head and thus permit both bifurcations to lie in the same plane to insure the stem 8 remaining in an upright position.

In using the toy, the body 1 is held in one hand while the stem 8 is grasped by the other hand and pulled upwardly, as shown in Fig. 5 and in Fig. 2 by the dotted lines. The stem is then released so as to permit the striking element to contract and fly back against the head 5, the bifurcations striking the latter successively so as to produce the reports. Since the body 1 is hollow, the reports will be very loud and resemble somewhat the bursting of a firecracker. A toy of this character is designed to afford considerable amusement and entertainment to chil-

dren and is of comparatively durable and substantial construction so that it will not be easily broken.

From the foregoing description, taken in connection with the accompanying drawings, the advantages of the construction and of the method of operation will be readily apparent to those skilled in the art to which the invention appertains, and while I have 10 described the principle of operation of the invention, together with the device which I now consider to be the best embodiment thereof, I desire to have it understood that the device shown is merely illustrative, and 15 that such changes may be made when desired as are within the scope of the claims.

Having thus described the invention, what I claim is:—

1. A toy comprising a hollow body having 20 an open end, a vibrant head stretched over the open end and secured to the body, a rubber strip extending across the head with one of its flat faces normally in contact with the latter, said strip being secured at its ends to 25 the body, and a stem on the side of the strip opposite from that in contact with the head and integrally connected with the strip to form a pull device whereby the strip can be drawn away from the head and released to 30 strike the latter.

2. A toy comprising a hollow body having an open end and a peripheral groove adja-

cent such end, a vibrant head stretched over the open end of the body and having its marginal portion confined in the groove of 35 the body, a fastening band extending around the body and engaging the said marginal portion of the head to hold the same in the groove, an elastic strip extending across and normally in contact with the outer surface 40 of the head and having its ends held in the groove by the fastening band, and a stem on the elastic member and extending outwardly at right angles thereto from the side opposite from that in contact with the head to 45 form a pull device for stretching the member in the operation of the toy.

3. A toy comprising a hollow body, a vibrant head stretched across the end of the body, an elastic strip extending diametrically over and normally in contact with the head and provided with a longitudinal slit extending short of both ends of the strip, means for securing the ends of the strip to the body; and a yielding central stem having 50 bifurcations of different lengths secured respectively to the portions of the member at opposite sides of the slit.

In testimony whereof I affix my signature in presence of two witnesses.

JOSEPH G. McCONAGHY.
